UNITED STATES PATENT OFFICE.

PROCTOR P. COOLEY, OF PEORIA, ILLINOIS, ASSIGNOR TO CULTER & PROCTOR STOVE CO., OF PEORIA, ILLINOIS, A CORPORATION OF ILLINOIS.

STOVE OR FURNACE.

1,162,904.

Specification of Letters Patent.

Patented Dec. 7, 1915.

Application filed September 15, 1913. Serial No. 789,770.

To all whom it may concern:

Be it known that I, PROCTOR P. COOLEY, a citizen of the United States, and a resident of Peoria, in the county of Peoria and State of Illinois, have invented a new and useful Improvement in Stoves or Furnaces, of which the following is a specification.

This invention relates to a new and useful improvement in a stove or furnace, and has particular reference to a draft regulating means formed on the stove or furnace door.

The principal object of this invention is the provision of a structure for the above named purpose which is simple in construction and operation, and which regulates the draft with accuracy, the construction providing an opening in the door which serves as a draft opening, and also to accommodate the shaker bar or grate.

Another object of this invention is the provision of a draft regulating means for a stove or furnace door which is so arranged as to permit the shaking of the grate with a minimum exposure of the ash-pit, thereby reducing the spread of dust and ashes to a minimum.

To the accomplishment of the foregoing and such other objects as may hereinafter appear, my invention consists in the construction, combination and arrangement of parts hereinafter described and then sought to be defined in the appended claims, reference being had to the accompanying drawings forming a part of this application and which show for illustrative purposes, a preferred embodiment of my invention, it being understood however that various changes may be made in practice within the scope of the claims without digressing from my inventive idea.

In the drawings: Figure 1 represents a front elevation of a stove or furnace door constructed according to my invention; Fig. 2 is a horizontal section on line 2—2 of Fig. 1, looking in the direction of the arrow; Fig. 3 is a horizontal section on line 3—3 of Fig. 1, looking in the direction of the arrow, and Fig. 4 is a perspective view of the inside of the slide or shutter.

Like characters of reference indicate corresponding parts throughout the figures.

The stove or furnace door is designated by the reference character 1, and has provided in the upper portion thereof the rectangular opening 2, beneath which is the

vertically extending elongated slot 3. The door, at the sides of the opening 2 is formed with the outstanding and circumscribing portions or ribs 4. Similar outstanding portions 5, extend vertically across the door, and are spaced relative to each other and to said slot. The vertical portions 4' of the outstanding portions or ribs 4 have the terminal shoulders or flanges 6. The outside of these ribs or outstanding portions 4 and 5 are smooth, so that the slide or shutter 7 may have practically an air-tight fit thereon. This slide 7 has a rectangular body portion 8, slightly larger than said opening 2 and adapted to rest on the outstanding portions or ribs 4 inside of said shoulders or flanges 6, which form guideways for said slide or shutter. Said slide or shutter also has the depending extension 9, which is positioned and slides on said outstanding portions or ribs 5, entirely covering said slot 3 when the slide or shutter is in its upper position, the edges 9' of said extension being reduced so that they are on the same plane as the edges of the body portion 8, the shoulders 10 formed by reducing the edges bearing against the inside of said outstanding portions or ribs 5 to provide a guiding means and a tight fit. The lower end of the depending extension is provided on its inner face with a raised portion 11, which rests on the smooth portion 12 between the outstanding portions or ribs 5. Near the upper end of said depending extension 9 where it joins the body portion 8 of the slide or shutter, is provided the lug or projection 13, which is tapered to fit the inclined walls 3' of said slot 3. This lug or projection 13 engages the ends of the slot 3, to limit the movement of the slide or shutter in either direction. An aperture 14 is formed in the depending portion 9 of said slide or shutter and passes through said lug or projection 13. Mounted in this aperture is the pin or post 15, which also passes through a housing 16 having the cap or head 17 secured on the end thereof, and a spring 18 positioned in said housing about said pin or post, and bearing against the head thereof, as shown. The other end of said pin or post is upset over a washer or bearing member 19, which rests and slides on the raised portion 20 which is provided along the edges of said slot on the inside of the door or opening.

By means of this construction it is seen that the slide or shutter, due to the smooth contact surface, has an air-tight engagement with the door. It may be adjusted in any position, and due to the action of the spring 18 will remain in that position until moved again. The opening 2 is located so that the shaker bar may be actuated, as is well understood. When necessary to shake the grate, the slide or shutter is moved downwardly to a slight distance, exposing a minimum amount of the draft opening, thereby reducing the spread of the dust and ashes to the smallest amount possible. This is an advantageous feature. It is therefore seen that I have provided a draft regulator which is simple in construction, having the advantage of being air-tight and readily adjustable. It is constructed of the fewest possible parts.

What I claim is:—

1. The combination with a door having a draft opening, and a slot below said opening, said door also having outstanding portions or ribs circumscribing said opening and outstanding portions or ribs extending parallel to and adjacent said slot, a slide or shutter member having a portion conforming in shape to said opening and adapted to engage said circumscribing outstanding portions or ribs, said slide or shutter having a depending extension adapted to rest and slide on said last mentioned outstanding portions or ribs, and means for slidably securing said slide or shutter to said door.

2. The combination with a door having a draft opening, and a slot below said opening, said door also having outstanding portions or ribs circumscribing said opening and outstanding portions or ribs extending parallel to and adjacent said slot, a slide or shutter member having a portion conforming in shape to said opening and adapted to engage said circumscribing outstanding portions or ribs, said slide or shutter having a depending extension adapted to rest and slide on said last mentioned outstanding portions or ribs, a lug or projection formed on the inside of said depending extension and adapted to be positioned in said slot, a spring controlled member passing through said depending extension and lug or projection and having securing means on the inner end thereof, whereby said slide or shutter is slidably and frictionally held in position on said door.

3. The combination with a door having a rectangular opening in the upper portion thereof and an elongated vertical slot below said opening, said door having outstanding portions or ribs circumscribing said opening, the side outstanding portions or ribs being extended downwardly and having shoulders or flanges along the edges thereof, said door also having outstanding portions or ribs ex-

tending parallel to said slot, a slide or shutter having a body portion slightly larger than said opening but conforming in shape thereto and positioned thereover with its ends located within said shoulders or flanges and having its inner bearing edges resting on said outstanding portions or ribs, said slide or shutter having a depending extension adapted to cover said slot when the slide or shutter is in its upper position and having its edges reduced and bearing on said second mentioned outstanding portions or ribs, the shoulders formed by said reduced edges engaging the inside edges of said second mentioned outstanding portions or ribs, and means for slidably and frictionally securing the slide or shutter on said door.

4. The combination with a door having a rectangular opening in the upper portion thereof and an elongated vertical slot below said opening, said door having outstanding portions or ribs circumscribing said opening, the side outstanding portions or ribs being extended downwardly and having shoulders or flanges along the edges thereof, said door also having outstanding portions or ribs extending parallel to said slot, a slide or shutter having a body portion slightly larger than said opening but conforming in shape thereto and positioned thereover with its ends located within said shoulders or flanges and having its inner bearing edges resting on said outstanding portions or ribs, said slide or shutter having a depending extension adapted to cover said slot when the slide or shutter is in its upper position and having its edges reduced and bearing on said second mentioned outstanding portions or ribs, the shoulders formed by said reduced edges engaging the inside edges of said second mentioned outstanding portions or ribs, and means for slidably and frictionally securing the slide or shutter on said door, said means including a stud or projection on the inside of said depending extension positioned in said slot, a pin or post passing through said depending extension and said lug or projection, a head on one end of said pin or post, a spring member about said pin or post and engaging said head to normally tend to hold it outward, and a bearing member secured to the other end of said pin or post which is on the inside of the door.

5. The combination with a door having a rectangular opening in the upper portion thereof and an elongated vertical slot below said opening, said door having outstanding portions or ribs circumscribing said opening, the side outstanding portions or ribs being extended downwardly and having shoulders or flanges along the edges thereof, said door also having outstanding portions or ribs extending parallel to said slot, a slide or shutter having a body portion slightly larger than said opening but conforming

in shape thereto and positioned thereover with its ends located within said shoulders or flanges and having its inner bearing edges resting on said outstanding portions or ribs, 5 said slide or shutter having a depending extension adapted to cover said slot when the slide or shutter is in its upper position and having its edges reduced and bearing on said second mentioned outstanding portions or 10 ribs, the shoulders formed by said reduced edges engaging the inside edges of said second mentioned outstanding portions or ribs, a lug or projection on said depending extension adapted to fit in said slot and to 15 limit the movement of the slide or shutter, and means for slidably and frictionally securing the slide or shutter on said door.

6. In combination with a door, having a draft opening and a slot below said opening, outstanding portions or ribs circum- 10 scribing said draft opening, certain of the outstanding portions or ribs having shoul- 15

ders or flanges along the edges thereof, a slide or shutter having a body portion slightly larger than said draft opening and 25 bearing on the bearing surfaces provided by said outstanding portions or ribs, said shoulders or flanges providing a guiding means for said slide or shutter, additional outstanding portions or ribs adjacent said 30 slot, said slide or shutter having a depending extension adapted to bear on the bearing surfaces provided by said last mentioned outstanding ribs or projections and resilient means passing through said slide or shutter 35 and said slot for slidably and frictionally holding said slide or shutter on said door.

In testimony whereof I affix my signature in the presence of two witnesses.
